UNITED STATES PATENT OFFICE.

JOHN J. McCOURT, OF BLOOMFIELD, NEBRASKA.

STOCK DRINKING-FOUNTAIN.

1,205,232.

Specification of Letters Patent. Patented Nov. 21, 1916.

Application filed April 5, 1913. Serial No. 759,146.

To all whom it may concern:

Be it known that I, JOHN J. McCOURT, a citizen of the United States, residing at Bloomfield, in the county of Knox and State 5 of Nebraska, have invented certain new and useful Improvements in Stock Drinking-Fountains, of which the following is a specification.

This invention relates to devices for supplying drinking water to stock and poultry, and has for its primary object the provision of a sanitary drinking fountain, which is provided with means for preventing the water maintained in the drinking trough 15 from freezing during cold weather.

Another object of this invention is the provision of a device of this nature which is strong and durable, and by means of which a considerable quantity of water may 20 be maintained at a temperature above freezing during cold weather at a reasonably small cost and little labor.

A still further object of this invention is to provide an improved drinking fountain 25 which will maintain a uniform level of water in the drinking trough; to surround the drinking trough with a vacuum or dead air chamber, which will aid in preventing the freezing of the water and to provide a novel 30 and efficient heating plant for the same.

With the foregoing and other objects in view, this invention consists in such novel features of construction, combination and arrangement of the various parts, as will be 35 hereinafter more fully described, illustrated in the accompanying drawings, and claimed.

In describing the invention in detail, reference will be had to the accompanying drawings, wherein like characters designate 40 like or corresponding parts throughout the several views, and in which:

Figure 1 is a side elevation of the improved drinking fountain; Fig. 2 is a longitudinal sectional view through the center 45 thereof; Fig. 3 is a cross sectional view taken on the line 3—3 of Fig. 1, and showing the heating apparatus removed from the fountain proper; and Fig. 4 is a side elevational view showing parts of the improved 50 fountain in a position different from that shown in the other views, and also showing parts in cross section.

Referring to the drawings by numeral, 1 designates the outer casing of the drinking fountain which is cylindrical in shape, being constructed of any desirable sheet metal or other material, and having its upper end closed by a closure 2 which is secured to the same in any suitable manner. The closure 2 has centrally located therein a depending 55 portion 3 which is provided with an internal screw-threaded aperture extending therethrough. A cap or closure 4, which is practically a combination funnel and cap, has depending members 5 and 6 secured to its 60 opposite ends, the depending member 5 being provided with external screw threads 65 which engage the internal screw threads of the member 3 when the body portion 1 of the drinking fountain has a sufficient amount 70 of water therein. The member 5 is secured to a cross bar 7 which is attached to the inner surface of the sides of the member 4, and passes diagonally across the member. The end 8 of the member 4, which has the 75 depending member 6 secured thereto, is curved outwardly, as is clearly shown by the drawings. A filtering screen 9 is mounted in the depending member 6 and tends to 80 keep all foreign particles which may be in the water out of the tank, which is formed by the outer casing 1, when the water is being poured into the same. When it is desired to pour water into the tank, the member 4 is inverted, and the depending member 6 is inserted into the member 3, and 85 water being poured into the open end of the member 4 will pass through the opening in the depending member 6, through the screen 9 and into the tank, as is clearly shown in 90 Fig. 4 of the drawings. When the member 4 is placed upon the closure 2 in the manner, as is illustrated in Fig. 2 of the drawings, an air-tight joint is formed between the two, and tends to create a vacuum 95 in the interior of the tank, after the same has been filled with water.

A compartment 10 is centrally located within the tank and secured to the bottom of the same, and having communication with the exterior of the tank through the opening 11 in the outer casing 1, which opening is closed by a sliding door 12. The door 12 is slidably mounted in guideways 13, which

are secured to the outer surface of the casing 1, and has a transparent member 14 mounted near the upper end of the same. The lower portion of the door 12 is provided with a 5 cut-out portion 15, which has a protector 16 formed of a piece of sheet metal bent thereabout, and secured to the door, as is shown in Figs. 1 and 2. This cut-out portion 15 forms a means for ventilating the interior 10 of the compartment 10, and for supplying the necessary amount of oxygen to keep the fire, which is ensuing from the heater or fire-box 17, burning.

The fire-box 17 may be of any suitable 15 type, but it is herein shown as consisting of a body portion or pan 18, having a handle 19 secured to one end thereof, and an opening 20 in its upper surface, through which oil, such as kerosene or gasoline, may be 20 poured. A wick-supporting member 21 extends upwardly from the upper side of the pan 18, and is substantially centrally located thereon. The heater 17 is inserted into the compartment 10 through the door 12, 25 and the transparent member 14 forms a means for determining whether the blaze of the wick has been extinguished or not, without necessitating the opening of the door. A ventilating pipe 22 is connected to one 30 end of the casing of the compartment 10, and extends vertically through the tank passing through the closure 2, and has a hood 23 mounted upon its upper end. A pipe 24, which has an opening in one end 35 communicating with the interior of the tank, passes through the compartment 10, directly above the wick-supporting member 21, so that the heat generated by the flames of the wick will be absorbed by the same. A short 40 distance from the opposite end of the compartment 10, through which the pipe 24 enters, the same is bent downwardly so as to extend vertically within the compartment until the same reaches a point near the bottom 45 of the compartment, where it is again bent outwardly so as to extend laterally in the compartment and passes outwardly through one end of the compartment communicating with the drinking trough 25. 50 The drinking trough 25 is securely connected to the lower end of the casing 1, and is surrounded by a vacuum or dead-air chamber 26. An opening 27, which has a short piece of pipe 28 mounted therein, communicates with the drinking trough 25, and forms 55 a second inlet for the trough from the tank.

When it is desired to fill the tank with water, plugs (not shown), of any suitable type are inserted into the pipe 28, and into 60 the opening in the pipe 24 which communicates with the drinking tank. The member 4 is then inverted, as is shown in Fig. 4 of the drawings, having the depending member 6 inserted within the member 3. Water

is poured into the member 4 and passes 65 through the same into the tank. When the tank is filled to the desired height, the member 4 is again inverted, having the external screw threads upon the member 5 in engagement with the internal screw threads of the 70 member 3, as is clearly illustrated in Fig. 2. This forms an air-tight closure for the opening within the member 3 and creates a vacuum within the interior of the casing 1. This creating of the vacuum within the casing 1 will cause the water, when the plugs 75 are removed from the ends of the pipe 24 and 28, to assume a definite level within the drinking trough 25 and remain constantly at this level. The vacuum chamber which 80 surrounds the drinking trough 25 is provided because of the fact that there being absolutely no air within this chamber, the cold air of the atmosphere will be prevented from contacting directly with the sides of 85 the drinking trough which contains the water, and thus greatly aid in preventing the water from freezing within the trough.

In practical fields, certain minor features 90 of construction, combination and arrangement of parts may necessitate alterations to which the patentee is entitled, provided such alterations are comprehended within the scope of what is claimed.

What is claimed is:—

1. In a stock drinking fountain the combination with an outer casing forming a tank, of a heating compartment secured to the bottom of said tank and having one end thereof communicating with the exterior of 100 the tank, means for heating said compartment disposed therein, a pipe disposed within said compartment extending directly over said heating means, one end of said pipe communicating with said tank, a trough the other end of said pipe, said pipe communicating with said trough, a second pipe communicating with said compartment and extending through said tank terminated exteriorly thereof, a pipe mounted in an opening in said casing and extending within said trough for the purpose set forth.

2. In a stock drinking fountain the combination with an outer casing forming a tank, of a heating compartment secured to the bottom of said tank, one end of said compartment terminating exterior of said tank, the other end of said compartment terminating midway the center and opposite side of said tank, heating means disposed within said compartment, a trough, a pipe disposed within said compartment, and extending directly over said heating means, one end of said pipe communicating with said tank, the other end of said pipe terminating exteriorly of said compartment and said tank and communicating with said trough, a second pipe communicating with

said compartment extending through and terminating exteriorly of said tank whereby to ventilate said compartment, a pipe mounted in an opening in said casing and extending within said trough, and means for admitting air within said compartment for the purpose set forth.

In testimony whereof I affix my signature in presence of two witnesses.

JOHN J. McCOURT.
